UNITED STATES PATENT OFFICE.

JAMES R. COUNCIL, OF NORFOLK, VIRGINIA.

DESIGN FOR A CASE FOR BOTTLED GOODS.

Application filed June 20, 1925. Serial No. 13,836. Term of patent 3½ years.

To all whom it may concern:

Be it known that I, JAMES R. COUNCIL, a citizen of the United States, residing at Norfolk, in the county of Norfolk and State of Virginia, have invented a new, original, and ornamental Design for Case for Bottled Goods, of which the following is a specification, reference being had to the accompanying drawing, forming part thereof.

The figure is a perspective view of a case for bottled goods, showing my new design.

I claim:

The ornamental design for a case for bottled goods, as shown.

JAMES R. COUNCIL.
